UNITED STATES PATENT OFFICE.

DAVID J. DORSEY, OF BATON ROUGE, LOUISIANA.

FUEL-OIL BURNER.

1,410,389.

Specification of Letters Patent. Patented Mar. 21, 1922.

Application filed April 22, 1921. Serial No. 463,669.

To all whom it may concern:

Be it known that I, DAVID J. DORSEY, a citizen of the United States, residing at Baton Rouge, in the parish of East Baton Rouge, State of Louisiana, have invented certain new and useful Improvements in Fuel-Oil Burners; and I do hereby declare the following to be a full, clear, and exact description of the invention, such as will enable others skilled in the art to which it appertains to make and use the same.

This invention relates to new and useful improvements in burners and particularly to oil burners.

15 The object of the invention is to provide an oil burner for use in connection with steam generating boilers, wherein novel means are provided for mixing steam with the oil to burn therewith, at the tip or 20 nozzle of the burner.

Another object is to so construct a burner of this character that when the portion which is normally subjected to the greatest wear, due to the heat of the burning oil 25 and steam, becomes worn, it may be readily removed and a new part substituted, thus obviating the necessity of supplying a new burner.

Another object is to provide a steam 30 jet nozzle which can be easily and quickly removed and replaced, when repairs or adjustments are needed, and which is held tightly in position to effectively prevent leakage of oil.

35 Other objects and advantages will be apparent from the following description when taken in connection with the accompanying drawing.

In the drawing:

40 Figure 1 is a side elevation of a burner made in accordance with the invention.

Figure 2 is a top plan view of the same, the steam and oil pipes being omitted.

Figure 3 is a vertical longitudinal central 45 sectional view through the burner.

Figure 4 is a vertical transverse sectional view on the line 4—4 of Figure 3.

Figure 5 is a plan view of the removable burner tip plate.

50 Referring particularly to the accompanying drawing, 10 represents a metal housing or casing having the chamber 11 therein, said casing being open at its lower side, and forward end, as shown at 12 and 13, respectively.

55 Screwed into the upper portion of the rear wall of the casing is the oil

pipe 14, the same being arranged to deliver oil into the casing. A steam pipe 15 is loosely engaged through an opening 10' in the rear wall of the casing 10, below the 60 oil pipe 14. The pipes 14 and 15 connect with a pipe 16, one portion 16' of which extends to a source of oil supply, while the other portion 16'' extends to a source of steam supply, neither of the said supplies being shown. A valve 17 is disposed in the pipe 16, between the points of connection of the pipes 14 and 15 with said pipe 16. By this arrangement, when the valve is open, steam will flow into and 70 through the pipe 15 to drive out any remaining oil. Normally the valve is closed so that the oil and steam do not mingle until they reach the nozzle of the burner.

Removably disposed in the lower portion 75 of the casing 10, and having the adjacent end of the steam pipe screwed thereinto, is a trapezoidal chamber 18, the same being formed with a passage 19 therethrough and over the forward end of which is formed 80 a metal plate 20, the same being the upper wall of the chamber 18. Engaged on the pipe 15, and bearing against the rear wall of the casing 10, is a packing washer 15', the same being pressed against the wall 85 by the nut 15'', which is screwed onto the pipe 15. This permits the chamber to be drawn tightly against the inner face of said rear wall, while the washer is pressed against the outer face thereof, with the 90 result that leakage of oil is prevented.

The lower portion of the front wall of the chamber 18 is formed with a forwardly and outwardly flared opening 21, which, when the device is in proper position, and in 95 conjunction with the wall 20, of the chamber, produces an elongated slot through which the steam is projected. The oil flows into the chamber 11, from the pipe 14, and drips onto the inclined wall 20, from whence 100 it runs down past the slot of the chamber 18. The steam, issuing from the slot, draws the oil down and mingles therewith, and projects the mixture beyond the casing 10, where it burns, on the upper face of the removable plate to be mentioned later herein.

Disposed against the bottom of the casing 10 is a metal plate 22, the forward end of which projects beyond the front of the casing, as shown at 23. The upper face of the 110 plate 22 is formed with an angular boss 24 which fits up into the lower portion of the

chamber 11, and forwardly from the forward open end of the casing. A pair of apertured lugs 22', extending from the opposite sides of the plate 22, to receive the 5 screws 25, are formed on the opposite side edge portions of the plate 22, said screws being engaged upwardly into the bosses 26, formed on the side walls of the casing. Disposed on the plate 22, and secured to the 10 side walls of the casing 10, by the screws 22', is a removable combustion plate 27, the same extending forwardly on the projecting portion 23 of the plate 22. It will be noted that the screws 25, which secure the plate 22 to the 15 casing, do not pass through the removable combustion plate 27, and that the screws 22' are concealed by the plate 22. The outer end of the plate 27 is wider than the casing to provide a broad surface on which the 20 flame is formed.

The mixture of steam and oil, which issues from the slot of the chamber 18, is directed against the upper face of the projecting end of the plate 27, where said mixture 25 is burned. When the plate 27 wears out, due to the great heat thereon, at the point of combustion of the oil and steam, the removal of the screws 25 will permit the removal of the plate 22, which uncovers the screws 22', 30 when these latter screws may be taken out and the plate 27 removed and a new one sub-

stituted. This obviates the necessity of replacing the whole burner, when the tip has been burned out. Furthermore, the oil being fed onto the upper wall of the casing or 35 chamber 18, becomes heated and is partially volatilized before coming into contact with the steam, with the result that the mixture of the oil and steam is more readily and effectively accomplished, and a better and 40 hotter flame formed.

What is claimed is:

An oil burner including a casing having oil and steam inlets in one end and a common discharge opening in the other end, the 45 casing having an oil passage leading from the upper portion downwardly to the discharge opening, a steam nozzle arranged to discharge beneath the oil passage, a renewable plate fastened within the casing 50 and extending outwardly therefrom in position to receive the steam and oil in combustion thereon, and a removable bottom plate for the burner, said plates being secured independently to the burner.

In testimony whereof, I affix my signature, in the presence of two witnesses.

DAVID J. DORSEY.

Witnesses:

W. M. BENTON,
MAUDE KEAN.
